UNITED STATES PATENT OFFICE.

NAPOLEON LOISELLE, OF SOUTH FORK, SASKATCHEWAN, CANADA.

GRAIN CARRIER.

Application filed June 16, 1924. Serial No. 720,399.

To all whom it may concern:

Be it known that I, NAPOLEON LOISELLE, a subject of the King of Great Britain, and resident of South Fork, in the Province of Saskatchewan, Dominion of Canada, have invented certain new and useful Improvements in Grain Carriers, of which the following is a specification.

This invention relates to improvements in grain carriers, for use on mowing and binding machines, and is an improvement on the grain carrier covered by my Canadian Patent No. 209,678, issued March 22nd, 1921, and the objects of the invention are to facilitate collecting the desired number of sheaves to form a shock and dumping the same at the place where the shock is to be set up, to permit of the carrier being dumped by the driver of the machine, to properly strengthen the carrier, and generally to adapt it to better perform the functions required of it.

With the above and other objects in view the invention consists essentially of the improved construction hereinafter described and set forth in the following specification and accompanying drawings forming part of the same.

In the drawings;

Figure 1 is an end elevation of a mowing and binding machine, showing the improved carrier mounted thereon.

Figure 2 is a plan view of the same.

Figure 3 is a perspective of the carrier.

Figure 4 is a section taken on the line 4—4 of Figure 2.

Figure 5 is an end elevation of the carrier.

Figure 6 is a section on line 6—6 of Figure 4.

Figure 7 is a section on the line 7—7 of Figure 2.

Figure 8 is a section on line 8—8 of Figure 7.

Like characters of reference refer to like parts in the several figures.

Referring to the drawings, A represents a mower and binder of any usual description, and B the improved grain carrier attached to the same and stubbleward of the machine.

The grain carrier underlies the deck 10 of the binder and consists of a rectangular receptacle open at one end and comprising a side wall 11, one end wall 12, an opposite wall 13 which is angularly disposed, the said walls being supported from a frame 14. The

bottom of the receptacle comprises a pair of 55 pivotally mounted doors 15 which are adapted to pivot adjacent their outer longitudinal edges, the inner edges being designed to abut when the receptacle is closed. The open end of the receptacle is formed with an inverted 60 U-shaped angle member 16 and from this U-shaped member a rod 17 extends towards the frame of the binder and is secured thereto. The frame 14 of the receptacle, at that end 65 adjacent to the wall 12, is provided with a rod 18 which extends towards the mower and binder and is rigidly connected thereto. The inverted U-shaped member 16 is braced by a diagonal rod 19 and from this U-shaped 70 member chains 20 extend which are connected to transverse bars 21 engaging with the upper face of the two portions of the bottom 15.

The doors 15 are pivoted at 15^a as illustrated more particularly in Figures 6, 7 and 8, and are also designed and provided with means so that when swung downwardly in vertical open position, they can be moved upwardly out of the way, this being accomplished by means of a casing 7 embedded in 80 the doors and pivotally connected to them at 15^b, the whole being supported by means of supporting brackets 8 of wire or suitable flexible metal bent over at their upper ends to engage with the sides of the carrier and 85 bent at right angles at their lower ends at 9 to form the supporting means for the doors 15. These supporting bracket members also perform the functions of tracks in combination with rollers 30 and 31 carried by the 90 doors on each side of their pivotal point 15^a, so that as above mentioned, when the doors are swung downwardly, vertically in open position as shown in dotted lines in Figure 6, they are adapted by means of said rollers 95 to be moved upwardly along the supporting bracket members 8 acting as tracks, also shown in Figure 6, and to be retained in this position by means of chains 20 on the member 16. 100

On the under face of the two portions of the bottom 15 rods 22 extend and these rods project beyond one edge of the frame 14 and are connected by a chain 23 to the crank arm 24 of a crank lever 25, the other arm 26 of which is connected to a lever 27 designed to be actuated by a hand lever 28 located at a point adjacent to the driver seat 29. When 105

- the desired number of sheaves have been delivered from the binder deck 10 into the receptacle B to form a shock the driver actuates the lever 28, thereby turning the crank 5 lever 27 and crank lever 25 allowing the two portions of the bottom 15 to open under gravity and the sheaves collected in the receptacle are thus dumped at the place in which they are to be set up as a shock.
- 10 When the sheaves have been dumped the driver actuates the lever 28 which through the crank levers 27 and 25 closes the two portions 15 of the bottom and the process of collecting sheaves is continued until the desired number has been collected, whereupon the collector B is dumped in the manner already described.

From this description it will be seen that I have invented a grain collector which can 20 be advantageously utilized on mowing and binding machines and on which the desired number of sheaves may be collected and dumped in a place in which a shock is to be set up.

25 As many changes could be made in the above construction, and many apparently widely different embodiments of my invention, within the scope of the claims, constructed without departing from the spirit 30 or scope thereof, it is intended that all matter contained in the accompanying specifi-

cation and drawings shall be interpreted as illustrative and not in a limiting sense.

What I claim as my invention is:

1. A grain carrier of the character described, comprising a receptacle having side walls, and an end wall, the other end being open, a bottom formed in two pivotally mounted portions, a crank lever, a chain 35 extending from the crank lever to the said portions, and means for operating the crank member.

2. A grain carrier comprising a receptacle, formed with a side wall, an opposite inclined side wall and an end wall, the other end being open, a bottom formed in two portions, supporting brackets adapted to engage with the side walls above said portions, means in said portions for pivotally mounting them in said brackets, rollers in said portions mounted to travel on the supporting brackets when the portions are swung into an open position, an inverted U-shaped member at the open end of the carrier, means for moving the portions of the bottom about their pivotal means to open position and means for retaining the bottom portions of the carrier in a raised position when moved upwardly into the carrier.

In witness whereof I have hereunto set 60 my hand.

NAPOLEON LOISELLE.
